UNITED STATES PATENT OFFICE.

PETER WECHT, OF BELLAIRE, OHIO.

GLASS-WORKING APPARATUS.

1,300,066.

Specification of Letters Patent.

Patented Apr. 8, 1919.

Application filed April 6, 1918. Serial No. 227,105.

To all whom it may concern:

Be it known that I, PETER WECHT, a citizen of the United States of America, and resident of Bellaire, county of Belmont, and State of Ohio, have invented certain new and useful Improvements in Glass-Working Apparatus, of which the following is a specification.

This invention relates broadly to glass working apparatus, and more specifically to a paste-mold and dipping apparatus therefor.

The primary object of the invention is to provide a paste-mold and improved mechanism for immersing the mold to effect cooling thereof.

A further object is to provide, in association with a glass mold and mold-cooling apparatus, means whereby figures, designs or patterns may be impressed in the bottom of the ware during the molding operation.

With these and other objects in view, the invention resides in the features of construction, arrangement of parts and combinations of elements which will hereinafter be described, reference being had to the accompanying drawings, in which—

Figure 1 is a top plan view of the invention, with a portion of the operator's platform broken away;

Fig. 2 is a sectional elevation on line 2—2, Fig. 1;

Fig. 3 is an enlarged side elevation of the mold elevating and lowering mechanism;

Fig. 4 is an enlarged section on line 4—4, Fig. 3;

Fig. 5 is a side elevation of the mold opening and closing mechanism;

Fig. 6 is a top plan view of the same;

Fig. 7 is an enlarged top plan view of the bottom-piece and the support therefor;

Fig. 8 is a longitudinal section of the same;

Fig. 9 is an enlarged top plan view of the mold support or base, showing a modified form of bottom-piece; and—

Fig. 10 is an enlarged section on line 10—10, Fig. 9.

Referring to said drawings, in which like designating characters distinguish like parts throughout the several views—

1 indicates a water container or tank which is preferably rendered portable by the provision of truck wheels, as 2. Disposed adjacent to the front end of said tank and arranged to be lowered into and ele-

vated from the water contained by said tank is a hinged sectional glass-mold 3. Said mold is mounted upon a suitable table-like mold base or support 4 which is carried by oppositely-disposed rack-bars 5 that are vertically movable for effecting raising and lowering of the mold-support 4. Said rack-bars are disposed in slidable relation to upright supporting standards 6 located within and at opposite sides of the tank, each thereof having a longitudinal tongue 7 of dove-tail form slidably received in a correspondingly shaped channel 8 provided in the adjacent standard.

Disposed in mesh with the teeth of each rack-bar 5 is a gear segment 9 carried by a transverse shaft 10 mounted in bearings carried by the tank. Also carried by said shaft 10 is a pinion segment 11 in mesh with the teeth of a vertical rack-bar 12 which has its upper end projected above the level of a platform 13 upon which the operator stands, said platform being suitably mounted, as upon a supporting frame or brackets 14 superposed on the tank. A foot-pedal 15 is carried by the projecting upper end of said rack-bar 12, as shown. Said rack-bar is carried by and has dove-tail sliding relation to an upright standard 16.

As is obvious, when the rack-bar 12 is forced downward by foot-pressure applied to the pedal 15, the shaft 10 is rotated rearward and, through the intermediate mechanism described, the mold is elevated from its normal lowered position to the dotted line position indicated in Figs. 2 and 3. The weight of the mold and mold-carrying parts serves to return the parts to their normal position when the elevating force is withdrawn.

A lever 17 fixed on said shaft 10 at a suitable point has a weight 18 adjustable thereon to approximately balance the weight of the elevatable parts, so that, to effect elevation of said parts, relatively slight foot pressure will suffice.

Carried by the mold base or support 4 is a rearwardly extending tail-piece 19 which carries thereon in alined relation to the mold two upright bearing members 20 and 21 in which a horizontal rod 22 is slidably mounted. Said rod carries upon its front end a cross-bar 23 to which are pivotally connected the rear ends of two links 45 which have their front ends similarly connected to the mold sections and which are designed, when

actuated to advance and retract by longitudinal shifting movement of said rod, to effect closing and opening, respectively, of said mold sections. A spiral spring 24 carried by said rod 22 has its front end resting against lug or member 20 and its opposite end seated against a fixed collar 25 carried by said rod, said spring serving to normally maintain said rod retracted, holding 10 the mold open, as is most clearly shown in Figs. 1 and 6.

Carried by the rear end of the rod 22 is an anti-friction roller 26, and engageable with said roller for effecting a forward, or 15 advancing, movement of said rod against the resistance offered by said spring 24 is the upwardly and forwardly inclined surface 27^a of a rod-shifting member 27 which is vertically movable upon an upright post 28, 20 having its lower end seated upon the upper end of a spiral spring 29 located in embracing relation to said post. An upright push-rod 30 carried by said member 27 projects above the level of the platform 13 and bears 25 a foot-piece 31 whereby force may be applied for depressing said member against the tension of its supporting spring 29. As is apparent, during the raising and lowering movements of the mold, the latter is held 30 open by the force exerted by the spring 24 which also serves to normally maintain the open condition of the mold while the latter occupies its elevated, or working, position. When the operator desires to close the mold, 35 35 foot pressure is applied to the member 27 and the latter is depressed from its normal position, indicated in full lines in Figs. 2 and 5, to the position indicated in dotted lines in said figures. When so depressed, 40 the inclined surface 27^a acts through the roller 26 to advance the rod 22 to mold-closing position, which position is maintained only so long as the depressing pressure applied to said member 27 is not released. 45

Located at a suitable point within the front end of the tank 1 is a post or like support 38 upon which is adjustably mounted one end of an arm-like bracket 32 having an 50 open longitudinal slot 33 in its outer end. Said slot is adapted to receive therein in vertical position a sleeve-like bearing 34 in which is rotatably held the spindle 35 of a bottom piece 36 which may have formed in its top 55 face any design or pattern, as the star 37 shown in Fig. 7, which it may be desired to form in the bottom of the article produced in the mold. Said arm 32 is so positioned on its support 38, and the sleeve-bearing 34 is so 60 positioned in the slot 33, that the bottom-piece 36 is supported at the appropriate height and in a centered or axial position with respect to the mold, as shown in Fig. 1. Said bottom-piece serves as a bottom for 65 the mold when the latter occupies its opera-

tive or blowing position, and, consequently, will impart to the bottoms of the blown articles any figure or design carried on its upper face. In practice, after the blowing of an article and before the mold is lowered, the 70 operator releases the depressing pressure applied to the rod-shifting member 27 which immediately resumes its normal elevated position, permitting the rod 22 to retract and open the mold, whereupon the latter may be 75 lowered without hindrance from said bottom-piece. Since said bottom-piece must be lubricated, it must be permanently maintained above the level of the water in the tank to prevent the removal of the lubricant. 80 This is provided for in the construction described in which the bottom piece is not lowered with the mold.

The table or mold-base 4 has therein an appropriately located opening 46 and an 85 open slot 39 leading outward from said opening, said opening and slot receiving the bottom-piece 36 and its supporting arm or bracket 32, respectively, as the mold is elevated and lowered with respect thereto. 90

The supporting arm 32 and bottom-piece 36 may be dispensed with when plain bottoms are to be formed in the ware, in which case the construction shown in Figs. 9 and 10 may be substituted therefor. This modified construction includes a circular shouldered disk 40 adapted to seat in the opening 46 of the table, which opening is preferably also shouldered, as shown at 41. Said disk has therein a radial slot 42 through which 100 may be introduced to a centered position the vertical stem 43 of a bottom plate 44 wherein the bottoms of the articles molded are formed. 95

What is claimed is—

1. The combination with a water-tank, of a mold support, a mold composed of hinged sections which are movable horizontally in opening and closing mounted on said support, said mold and its support being movable vertically into and out of the water in said tank, means normally tending to maintain said mold open, means operable to overcome said tendency and to close said mold when the latter occupies working position, 115 and a rotatable matrix-like bottom-piece for said mold stationarily supported in working position and past which said mold moves axially in its travel into and out of the water. 120

2. The combination with a water-tank, of a mold composed of hinged sections which move horizontally to and from closed positions, said mold normally occupying a lowered position in the water in the 125 tank, manually actuated means for elevating said mold, means normally maintaining the mold sections in open position, shiftable means operable only when the mold occupies working position whereby the sections may 130

be closed, and a rotatable bottom-piece for said mold permanently disposed in working position and past which said mold travels in an axial direction in moving into and out of the water, said bottom piece having a design formed on its face.

3. The combination with a water-tank, of a vertically movable mold support, a sectional mold mounted upon said support and movable therewith, said support and said mold normally occupying a lowered position in the water in the tank, manually actuated means for elevating said parts, resilient means maintaining the mold open with its sections relatively stationary during movement of the mold to and from operative position, means operable when the mold occupies operative position whereby said mold sections are closed, and a rotatable bottom-piece for said mold having a figure or design on its face, said bottom-piece being permanently supported in operative position and past which said mold travels in an axial direction in moving into and out of the water.

4. The combination with a water-tank of a mold support vertically movable into and out of the water in said tank, a mold composed of horizontally movable hinged sections mounted on said support and movable with the latter, means normally holding said sections in positions maintaining the mold open, means operable only when the mold is in working position whereby said sections are moved to closed positions, a rotatable bottom-piece cooperating with the mold when the latter is in working position, and having a design formed on its face and a stationary arm supporting said bottom-piece in working position, said support having therein an opening for the reception of said bottom-piece and an open slot leading outward from said opening for the reception of said arm, said opening and slot permitting free vertical movement of said support with respect to said bottom-piece and said arm when the movable parts are lowered into and elevated from the water.

5. The combination with a water-tank, of a mold support vertically movable into and out of the water in said tank, a mold composed of hinged horizontally movable sections mounted on said support, resilient means normally holding said mold sections

in open position, manually actuated means operable only when the mold is in working position whereby said mold is closed against the tension of said resilient means, and a rotatable bottom-piece stationarily supported in a position wherein it cooperates with said mold when the latter is in closed working position said bottom piece having a configured matrix face, said support having an opening therein which permits vertical travel thereof past said bottom-piece in its movement to and from its lowered position and in which said bottom-piece is received when the parts occupy working position.

6. The combination with a water-tank, of a mold support movable in the line of its axis into and out of the water in said tank, a sectional mold mounted on said support, yieldable means normally tending to hold the mold sections in open position, means whereby said sections are closed against the tension of said yieldable means, and a rotatable bottom-piece stationarily supported in a position wherein it cooperates with said mold when the latter is in closed working position said bottom piece having a configured matrix face, said support being apertured to permit a vertical movement thereof without hindrance from said bottom-piece.

7. The combination with a water-tank, of a table-like mold support having an opening therein, said support being vertically movable into and out of the water in said tank, a mold composed of hinged-connected horizontally-closable sections mounted on said support, means normally tending to maintain said mold sections in open position, manually actuated means operable when said mold occupies working position to overcome said tendency and to close said mold sections over said table opening, and a rotatable member having a configured matrix face permanently occupying a position wherein it is received within said table opening when the table occupies working position and wherein it constitutes a bottom for the mold when the latter is closed.

In testimony whereof, I affix my signature in presence of two subscribing witnesses.

PETER WECHT.
